UNITED STATES PATENT OFFICE.

HENRY E. DECKERBACH, OF CINCINNATI, OHIO.

COMBINED COOLER AND CARBONATOR FOR LIQUIDS.

1,075,408.

Specification of Letters Patent.

Patented Oct. 14, 1913.

Application filed January 2, 1909. Serial No. 470,494.

To all whom it may concern:

Be it known that I, HENRY E. DECKERBACH, a citizen of the United States of America, and resident of Cincinnati, county of Hamilton, State of Ohio, have invented certain new and useful Improvements in Combined Coolers and Carbonators for Liquids, of which the following is a specification.

The object of my invention is an improved means for cooling and carbonating liquids, especially beer, whereby these operations may be effected more thoroughly, and the two operations may be carried on in a smaller space and may be completed in a shorter period of time, than heretofore.

Figure 1 is a sectional view of a carbonator and cooler embodying my invention, taken upon line $x-x$ of Fig. 2, showing one end of the cooling chamber and cooling coils broken away. Fig. 2 is an end elevation of the same. Fig. 3 is an elevation of the inner side of the head of the cooling chamber, but showing the sprayer head partially broken away. Fig. 4 is an enlarged view 25 of the end of the gas admission pipe.

Referring to the parts: The cooling chamber consists of an elongated cylindrical casing, A, at one end of which the liquid to be cooled is admitted, and from the opposite end of which the cooled liquid is withdrawn in any suitable manner. The discharge end of the cooling chamber is not shown, since it may be of the usual construction, without affecting the operation of my invention. Within the cylinder, A, cooling coils, B, are located, for the circulation of cold brine or ammonia. The head, A², of the cylinder has formed integral with it a centrally externally screw-threaded circular flange, a, which receives a cylindrical coupling, A³, to which the admission pipe, D, for the liquid to be cooled and carbonated is attached. Flange, a, surrounds a central perforation, the inner walls of which are screw-threaded to receive a nozzle, E, which has inwardly projecting arms to the inner end of which a perforated baffle plate, e', is secured so as to stand in front of the nozzle, E. Head, A², has an internal annular flange, a', which is externally screw-threaded to receive a perforated sprayer head, F, whose end stands adjacent to the end of the coils, B.

Coupling, A³, is perforated upon one side to receive the pipe, G, which leads from the reservoir, not shown, which holds the gas

under pressure. To the inner end of the pipe, G, a central exit pipe, g, is coupled. Pipe, g, terminates at its end in a perforated disk, g', and stands in the axis of the nozzle, E, and terminates adjacent to the end thereof. Upon the gas pipe, G, a pressure gage, g², is secured, and between the gage, g², and the coupling, A³, the cock, g³, is interposed. Adjacent to the gage, g², is 35 a reducing valve, g⁴.

The operation is as follows: The beer to be cooled and carbonated is admitted to the pipe, D. Its pressure is indicated by the gage, d. Suppose this pressure should be 70 twenty-five pounds: The reducing valve, g⁴, is then adjusted so that the gage, g², will indicate a pressure for the gas in the pipe, G, slightly greater than the pressure of the beer, say twenty-eight pounds. Then the 75 cock, g³, is opened. The beer discharged from the nozzle, E, strikes the baffle plate, e', is spread and sprayed by the same, this spraying being increased by the sprayer head, F. The beer, therefore, at the nozzle, 80 E, and within the surrounding sprayer head, F, is in a finely diffused state. The gas is ejected from the pipe, g, into this finely sprayed liquid and is thus thoroughly admixed therewith. The agitation of the liquid is continued after it is emitted from the sprayer head by its contact with the coils, B. This thorough agitation of the beer facilitates its dissolving the carbonic acid gas emitted from the pipe, g, an action which is 85 accentuated by the fact that the beer is being cooled at the same time that the carbonic acid gas is being injected into it.

What I claim is:

1. In combination in a carbonator for liquids, a cylindrical casing having an inlet port, a sprayer head mounted on the interior of the casing over the port, a liquid delivery pipe communicating with the port, a nozzle communicating with the port, a perforated baffle plate in front of said nozzle and inclosed by the sprayer head, a gas pipe projecting into said fluid delivery pipe and terminating in the nozzle and a perforated disk over the end of the pipe. 95

2. A carbonator and cooler for liquids, comprising a cylindrical casing, a liquid agitating and cooling coil located therein, a carbonator head having a liquid inlet port and removably secured to the casing, a nozzle secured to the head over the liquid inlet port, a liquid inlet pipe communicating with 100

105

110

the liquid inlet port, a gas inlet pipe having a perforated disk over the end of said pipe, located within the liquid inlet pipe and projecting into the nozzle, a perforated baffle plate located near the opening of the nozzle, and a perforated sprayer head secured to the carbonator head and inclosing the liquid

inlet port, the gas inlet pipe, the nozzle and the perforated baffle plate.

HENRY E. DECKEBACH.
